UNITED STATES PATENT OFFICE.

WILLIAM T. MITCHELL AND CHARLES S. SEWELL, OF RIDGELY,
MARYLAND.

CORN-THINNER'S VEHICLE.

SPECIFICATION forming part of Letters Patent No. 716,735, dated December 23, 1902.

Application filed August 28, 1902. Serial No. 121,273. (No model.)

To all whom it may concern:

Be it known that we, WILLIAM T. MITCHELL and CHARLES S. SEWELL, citizens of the United States, residing at Ridgely, Caroline 5 county, Maryland, have invented certain new and useful Improvements in Corn-Thinners' Vehicles, of which the following is a specification.

The invention relates to wheeled supports for persons engaged in thinning corn and for other purposes.

The objects of the invention are to provide a vehicle with a suitable seat or support on which a person may sit in proper position to readily reach and pull the superfluous stalks of young corn for the purpose of thinning the hills as the vehicle is drawn along the row; also, to provide means for raising and lowering the seat or support for different heights 20 of corn; also, to so construct the seat or support as to provide supports for the operator's legs; also, to construct the vehicle with seats or supports for two operators to enable them to thin two rows of corn at the same time; 25 also, to provide independent means for adjusting the height of said seats or supports, and also to provide a simple and effective draft mechanism. These objects are accomplished by the construction illustrated in the 30 accompanying drawing, in which the figure is a perspective of our improved vehicle.

A designates the rear axle, provided with the ground-wheels $a a$, adapted to run in parallel furrows, and A' is the V-shaped reach, 35 formed of two members $a' a'$, secured at their rear divergent ends to the axle A and connected at their front converging ends by a head A², having a vertical opening in which turns the vertical steering-shaft B, carried by the short front axle B', provided with the 40 small wheels b. The front end of the reach A' may be adjusted vertically on the shaft B by means of a vertically-adjustable collar b² or in any other suitable manner. A³ is a 45 cross-bar secured at its middle to the forward part of the reach in rear of its head A², and the lower side of this cross-bar is provided with three depending brackets A⁴, the middle one being wider than the end ones. The 50 wheeled frame thus formed may be of any suitable material, though we prefer to make

the parts A A' A³ of piping, and the brackets A⁴ are of strap or bar iron bolted to the cross-bar A³. It will be seen that this frame is supported at a height to be out of the way of 55 the growing corn and will not injure it by contact.

C C designate the horizontally-disposed seats for the operators, and these seats are each formed with two forwardly-diverging 60 members c c, along which the legs of the operator may extend. The front ends of these diverging members c c are loosely secured to the bottom members of the depending brackets A⁴ by means of single bolts c'. The outer 65 members of the members c are secured in the two outer brackets, while their inner members are both secured in the middle brackets. The brackets A⁴ may be formed in one piece or as three separate brackets, as may be pre- 70 ferred.

Each seat C is provided with a back C', provided at its upper end with an umbrella or shade support U. The rear ends of the seats are supported by means of the rearwardly and upwardly curved arms d, connected to the forward ends of the vertically-rocking levers D, pivoted between their ends upon the rear axle. Each lever has mounted thereon any suitable form of latch D', which 80 latches engage the toothed segments D², secured rigidly to the rear axle.

The singletree F is connected to a lug a², projecting forwardly from the head A², so that the draft will be in line with the reach 85 or horizontal body of the frame, and the rear cross-bar g of the thills G is rigidly connected, as by a square opening, to the upper squared end of the steering-shaft B, so that the wheels will be turned from the thills to 90 steer the vehicle.

The operation is as follows: The operators will seat themselves on the seats, facing forward, with their legs resting on the diverging seat extensions c c, which will bring the operators down close enough to the rows of corn to enable them to reach down through the openings between the leg-spaces and as the horse steadily pulls the vehicle along pull up the corn. We have found that by our machine corn-thinning is robbed of its back-breaking feature, and not only so, but a far 100

greater amount of work may be accomplished in a given time, thus saving the farmer considerable expense.

It is obvious that the machine may be used for a number of other purposes, such as weeding and planting and even in gathering certain crops.

What we claim is—

1. A corn-thinner's vehicle comprising, a frame having ground supports and an elongated horizontally-disposed seat or support suspended at its front and rear ends below the frame, substantially as set forth.

2. A corn-thinner's vehicle comprising, a horizontal wheeled frame to straddle the rows, seats suspended from the frame and having hand-openings.

3. A corn-thinner's vehicle comprising, a horizontal wheeled frame, seats suspended from the frame and having forwardly-projecting, diverging or spaced leg-supporting extensions.

4. A corn-thinner's vehicle comprising a wheeled frame having a forward cross-bar provided with depending brackets, horizontally-disposed seats mounted on their forward ends in the lower ends of said brackets and adjustably supported at their rear ends, substantially as set forth.

5. A corn-thinner's vehicle, comprising a wheeled frame, V-shaped horizontal seats supported at their front divergent ends from the forward end of the frame, and means for supporting and adjusting the rear ends of said seats, substantially as set forth.

6. A corn-thinner's vehicle comprising a wheeled frame having depending brackets at its forward end, adjustable levers at its rear end, and horizontally-disposed seats suspended from said brackets and levers, substantially as set forth.

7. A straddle-row corn-thinner's vehicle, having suspended therebelow a horizontal seat provided with forwardly-extended leg-

supporting members, substantially as set forth.

8. A corn-thinner's vehicle of the character described comprising a rear wheeled axle, a reach, a short wheeled front axle having a vertical shaft mounted in the front end of the reach, a cross-bar secured to the reach adjacent to its front end and provided with depending brackets or supports, seats hung at their front ends on said brackets or supports, rocking levers mounted on the rear axle and connected to the rear ends of the seats, toothed segments secured to the rear axle and latches mounted on said levers and engaging said segments, substantially as set forth.

9. A corn-thinner's vehicle having suspended therebelow a horizontally-disposed V-shaped seat provided at its rear end with a back, substantially as set forth.

10. A corn-thinner's vehicle comprising the rear wheeled axle, the reach having a head at its front end the steering-wheel having a shaft extending up through said head, the thills fixedly secured to the upper end of said shaft, a singletree secured to the said head and seats suspended from the frame between the front and rear wheels.

11. A corn-thinner's vehicle of the character described comprising a wheeled frame vertically adjustable at its forward end, horizontally-disposed seats supported at their front divergent ends from the forward end of the frame and adjusting mechanism supporting the rear ends of the seats from the rear end of the frame, substantially as set forth.

In testimony whereof we affix our signatures in presence of two witnesses.

WILLIAM T. MITCHELL.
CHARLES S. SEWELL.
